(57) **CLAIM**

The ornamental design for a digital process calibrator, as shown and described.

DESCRIPTION

FIG. 1 is a front view of a first embodiment of digital process calibrator in a closed arrangement.

FIG. 2 is a back view thereof.

FIG. 3 is a top view thereof.

FIG. 4 is a bottom view thereof.

FIG. 5 is a left side thereof.

FIG. 6 is a right side view thereof.

FIG. 7 is a first perspective view thereof.

FIG. 8 is a second perspective view thereof.

FIG. 9 is a third perspective view thereof.

FIG. 10 is a fourth perspective view thereof showing the tilt stand in a closed arrangement.

FIG. 11 is a fifth perspective view similar to FIG. 10 showing the tilt stand in an open arrangement.

FIG. 12 is a front view of a second embodiment of digital process calibrator in a closed arrangement.

FIG. 13 is a back view thereof.

FIG. 14 is a top view thereof.

FIG. 15 is a bottom view thereof.

FIG. 16 is a left side thereof.

FIG. 17 is a right side view thereof.

FIG. 18 is a first perspective view thereof.

FIG. 19 is a second perspective view thereof.

FIG. 20 is a third perspective view thereof.

FIG. 21 is a fourth perspective view thereof showing the tilt stand in a closed arrangement; and,

FIG. 22 is a fifth perspective view similar to FIG. 21 showing the tilt stand in an open arrangement.

The broken lines form no part of the claimed design.
